UNITED STATES PATENT OFFICE.

GEORGE A. JOHNSON, OF CHICAGO, ILLINOIS, ASSIGNOR TO WILLIAM H. MINER, OF CHAZY, NEW YORK.

ROLLER SIDE BEARING.

1,290,214.

Specification of Letters Patent.

Patented Jan. 7, 1919.

Application filed February 5, 1917. Serial No. 146,616.

To all whom it may concern:

Be it known that I, GEORGE A. JOHNSON, a citizen of the United States, residing at Chicago, in the county of Cook and State of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

The object of the invention is to provide a roller side bearing more particularly adapted for railway cars, and which consists of 15 few parts of relatively inexpensive construction and so arranged as to minimize danger of getting out of order.

In the drawing forming a part of this 20 specification, Figure 1 is a longitudinal section showing a side bearing embodying my improvements, the figure also showing in section, portions of a body bolster and a truck bolster of a car, and Fig. 2 is a trans- 25 verse sectional view of the side bearing and taken substantially on the line 2—2 of Fig. 1.

In said drawing, 10 denotes the truck bolster of a railway car to which the roller side bearing is preferably secured, and 11 indicates the body bolster of a car or bearing 30 plate secured thereto.

In the drawing, I have shown the side bearing applied to the truck bolster, the side bearing comprising a base casting A, anti-friction roller B, and combined spring and wear-plate C. The base casting A, as shown, 35 is of substantially hollow box-like form and comprises parallel side walls 12—12, end walls 13—13, lower wall 14 having extended flanges 15—15 by which it is riveted or otherwise secured to the truck bolster. The side 40 walls are preferably recessed, as indicated at 16, to facilitate the washing out or clearance of dirt or other foreign matter that might 45 accumulate in the side bearing. At their upper ends, the end walls 13 are provided with inwardly extending flanges 17 for a short distance, the latter at their extreme inner

edges being beveled, as indicated at 18, to thereby form suitable stops to limit the 50 movement of the roller B, as clearly indicated by the dotted lines in Fig. 1. The roller B is of usual construction and is adapted to roll in either direction from central or normal position. The roller is mounted on 55 the plate C which has a lower horizontal bearing or wearing flat surface 19 riveted to the base casting A. At its ends, the member C is provided with upwardly and inwardly extended curved leaf springs 20—20, 60 both of the latter being preferably slightly curled at their upper edges, as indicated at 21, where the same contact with the roller.

With the arrangement above described, it is apparent that the two leaf springs 20, 65 which are formed integrally with the wear surface 19, will hold the roller in normal position when the roller is free from the body bolster 11. When the roller is rolled to either side of normal, it is apparent that the 70 corresponding leaf spring will be flexed outwardly and downwardly to the position indicated by dotted lines at 20' in Fig. 1, and upon release of the pressure on the roller the spring will throw the roller back to normal position. It will also be noted that the leaf springs 20 engage the roller at points above a horizontal plane, passing through 75 the axis of the roller, thus serving to prevent the roller from being accidentally displaced. 80

I claim:

In a roller side bearing, the combination with a hollow casing, of a roller mounted within said casing, and a wear-plate on which said roller moves, said wear-plate 85 being secured to the casing and having integral leaf spring portions at each end thereof extended to engage the opposite sides of the roller to maintain the latter in normal position. 90

In witness that I claim the foregoing I have hereunto subscribed my name this 31st day of Jan. 1917.

GEORGE A. JOHNSON.

Witness:

JOSEPH HARRIS.
